JAMES F. MAYS, OF BIRMINGHAM, ALABAMA, ASSIGNOR TO MAYS ACCOUNTING MACHINE COMPANY, OF LEXINGTON, NORTH CAROLINA, A CORPORATION OF NORTH CAROLINA.

ACTUATING MECHANISM FOR CALCULATING-MACHINES.

1,323,894.

Specification of Letters Patent.

Patented Dec. 2, 1919.

Application filed January 31, 1918. Serial No. 214,717.

To all whom it may concern:

Be it known that I, JAMES F. MAYS, a citizen of the United States, residing at Birmingham, in the county of Jefferson and 5 State of Alabama, have invented certain new and useful Improvements in Actuating Mechanism for Calculating-Machines, of which the following is a specification.

This invention relates to improvements 10 in calculating or adding machines and the like and more particularly to improved actuating mechanism for the dials performing the calculating functions.

The primary object of the invention is 15 the provision of means for obtaining what may be termed a lost motion driving connection in the dial actuating mechanism.

Another object of the invention is to provide in a key actuated calculating machine 20 means common to the dial actuating mechanism and controlling means for the carry mechanism whereby the number of parts is reduced to a minimum and the structure is greatly simplified.

25 Further objects of the invention are to improve the key touch of machines of this class and particularly those of the key-actuated type, to take up automatically backlash between the teeth of the gears which actuate 30 the dials, and to otherwise improve the dial-actuating mechanism in the respects herein-after noted.

In general my invention is shown applied to that type of calculating machine in which 35 there are independent actuating mechanisms for adding dials of different orders or denominations which actuating mechanisms are individually operated by manipulative means such as series or banks of depressible 40 keys, but it is not intended to limit the invention to such type of machine.

Each dial actuating mechanism, which is operated by the keys on their down stroke, comprises a pinion which through a ratchet 45 and pawl construction operates the corresponding adding dial. A slot and pin connection between the pinion and an element carrying the pawl permits the pinion to advance one step before the pawl is moved 50 to rotate the dial. The pawl carrying mem-

ber is retained in normal position until the pinion has advanced one step at which time the pin of the slot and pin connection is in position to start to operate the pawl carrying element. Upon return movement of the 55 actuating mechanism the pawl carrying element is arrested in normal position by a stop member and the pinion moves an additional step to normal position.

The aforesaid pinion of each dial actuating mechanism is operated by a segment fast on a shaft which is rotated differentially by the series of keys appropriate thereto. During the first step of rotation, the shaft operates controlling means for the carry mechanisms. During this first step the dial is not operated because of the lost motion connection in the actuating mechanism.

In the present invention I employ many 70 of the features of construction and arrangement of parts fully shown and described in my copending application for Letters Patent of the United States Serial Number 148,559, filed February 14, 1917, wherein supplementary shafts are operated on the 75 initial down stroke of the keys and before shafts forming part of the dial actuating mechanisms are operated by the keys. In the present invention the supplementary shafts are eliminated and the functions performed by them are accomplished by the 80 shafts forming part of the actuating mechanism as above generally explained. In the particular form of embodiment disclosed herein the above explained lost motion connection is provided to permit operation of the control means for the carry mechanisms 85 before the rotation of the dial is begun.

While I have shown the invention in the 90 illustrative form disclosed herein applied to a machine of the type disclosed in the aforesaid copending application, it is not intended to limit the invention thereto as it is equally well applicable to other types of calculating machines without departing 95 from the scope of the invention.

Other objects of the invention will more 100 fully appear from the following description.

In order to more fully understand my

present invention reference will be had to the accompanying drawings wherein:—

Figure 1 is a partial vertical section from front to rear of the machine showing one column of keys in elevation and showing the dial operating mechanism controlled thereby.

Fig. 2 is an enlarged cross sectional view taken on line 2—2 of Fig. 3.

Fig. 3 is a section on the line 3—3 of Fig. 1.

Fig. 4 is a detail view showing in front elevation one of the escapement pawls and operating connections for the carry mechanism.

Similar reference numerals refer to similar parts throughout the several views in the drawings.

The machine illustrated in the accompanying drawings comprises, among other parts, a machine casing having a top 1, a back plate 2, a vertical partition 3 interposed between the banks of keys 4 on one side and the operating mechanism for dials 5 on the other side, which dials are mounted 20 on shafts 6 journaled at their rear ends on a bearing bar 7 and at their forward ends in a cross bar 8. Below the banks of keys is a guide plate 9 provided with holes to receive and form a bottom guide for the lower 25 ends of the key stems which at the end of their down stroke engage a base plate 10 of the machine.

The key stems of the "7", "8" and "9" keys are provided with rack teeth 11 as seen 30 in Fig. 1. These teeth on each key are adapted to mesh with teeth of its respective toothed sector 13, one of which is made fast on each rocker shaft 14 opposite the "7", "8" and "9" keys of each column. Each 35 of the keys of lower value than "7" in each column carries a pin which projects into a slot in the forward end of a lever 17, 17^a, 17^b, 17^c, 17^d, or 17^e as the case may be, each of these levers projecting at their rear 40 ends through slots in the back plate 2 and having a pivoted bearing on pins (not shown) in a bracket 19 fast to the back plate 2. A common rack key 21 carries a stepped cross bar 22 disposed to be engaged 45 by the levers 17, etc., and to be moved downwardly thereby to different distances depending on the value of the key depressed. Each rack key 21 carries teeth 11 adapted to mesh with teeth on its respective sector 50 13 on shaft 14 and serve to rotate the latter. The levers 17, etc., are pivoted at different distances from the rack key 21 and the bar 22 is stepped so that the rack key 21 is moved differentially from a uniform key movement. The rack bar is slidably mounted in 55 guide plates 26 and the plate 9 and is returned to normal position by springs 25 connected to pins 24 on the bar 21 and the guide plates 26. The keys are also returned to 60 normal position after being depressed by suitable springs 23. The "7", "8" and "9" keys and the common rack key 21 carry pins (not shown) coöperating with arms (not shown) on the sectors 13 to rotate the sectors for the purpose of bringing the teeth on the appropriate sector into engagement with teeth 11 on the key or common rack key depressed. The construction so far described is fully shown and described in the aforesaid copending application.

The driving mechanism for each dial comprises a toothed sector 36 fast on the forward end of the shaft 14 and meshing with a pinion 37 which together with its hub 105 turns 70 freely on a hub 106 of a wheel 107 loose on the dial shaft 6. The rear ends of the hubs 105 and 106 abut against a collar 108. A spring 109, coiled about the hub 105, is connected at one end to a pin 110 on the pinion 37 and at its opposite end to a pin 111 75 which is carried by the wheel 107 and projects through a slot 112 in the pinion 37. The wheel 107 carries a pawl 113 (Fig. 2) which is held in engagement by a spring 119 with the teeth of a ratchet wheel fast 80 on the shaft 6. A projection 114 on the wheel 107 normally engages a projection 115 on a bar 116 (Fig. 3) which is common to all of the wheels 107 of different denominations.

Upon depression of a key the pinion 37 is rocked counter-clockwise, as viewed in Fig. 3, through the shaft 14 and segment 36. The pin 111 is normally in engagement with the left hand end of the slot 112 as viewed 85 in Fig. 3. During the first step of movement of the pinion 37 from normal position, the tension of spring 109 is relaxed but it regains its normal tension upon the return movement of said pinion. When the pinion 100 37 completes its first step of advance the right hand end of the slot 112 engages the pin 111 so that upon continued advancement of the pinion 37, the wheel 107 and therefore the ratchet 38, shaft 6 and dial are advanced with it. The pinion 37 is returned 105 to normal position with the sector 36 and shaft 14 responsive to a coil spring 39 on the shaft 14. The pawl carrying wheel is returned to normal position with the pinion 37 and it is arrested in normal position by engagement of its projection 114 with the projection 115 on the bar 116.

From the above description it can be seen 110 that the pinion 37 travels one step more from normal position than the wheel 107, as the pinion 37 advances its first step with a lost motion effect which does not impart movement to the wheel 107 and hence to the ratchet 38, shaft 6 and dial. The dial is rotated the number of steps corresponding 115 exactly to the number of the key depressed and therefore the pinion 37, sector 36 and shaft 14 are rotated an extra step by the key. Upon the return stroke of the key 120

the pinion 37 and wheel 107 reverse their movement and when the wheel 107 reaches normal position its projection 114 engages the projection 115 on the bar 116 bringing the wheel to a stop, the pinion 37 being permitted to move an additional step to normal because of the slot and pin connection.

Fast on the forward end of the shaft 14 is a cam 81 coöperating with a dolly roll 85 10 on an arm 86 fast on a rocker shaft 87 journaled in brackets 88. An arm 90 fast on the shaft 87 is connected by a vertical link 91 to one arm of a bell crank lever 92, (Fig. 4,) which carries on its other arm a toothed 15 segment 93. The segment 93 meshes with a gear 96 carrying a crank pin 98 which is connected to one end of a pull bar 99. The other end of the bar 99 is pivotally connected to a bracket 100 connected to a reciprocating bar 101 that is mounted upon the several arms 73 of locking escapement pawls 20 75 and 77. The cam 81 and dolly roll 85 are so constructed that the shaft 87 is rocked during the first step of movement of the 25 shaft 14 upon down stroke of the keys. This rocking movement of the shaft 87 through the arm 90, bell crank lever 92, gear 96, pull bar 99 and reciprocating bar 101 operates the pawls 75 and 77. Such operation 30 of the pawls 75 and 77 locks a wheel 60 of the carry mechanism for each dial against operation during actuation of the dials and releases a toothed wheel 68 fast on the dial shaft 6 to permit actuation of 35 the dial. During the last step of return movement of the shaft 14, the shaft 87 and the above described parts operated thereby are returned to normal position by a coil spring (not shown) mounted on the shaft 40 87. The carry mechanism is shown partially in cross section in Fig. 1 but is not described in detail here as it is fully shown, described and claimed in the aforesaid copending application in which the cam 81, dolly roll 85 45 and operating connections, shown in Fig. 4, between the dolly roll and bar 101 are also more fully shown and described.

In said copending application, however, the cams 81 are mounted on supplementary shafts below the shafts 14 and a supplementary shaft is operated on the initial part of the down stroke of a key and before the key begins to rotate the shaft 14 so that the pawls 75 and 77 are operated to lock the 50 wheels 60 of the carry mechanism and release the wheels 68 to permit operation of the dial by the actuation of the shaft 14 and intermediate actuating mechanism. In the present invention the shafts 14 perform the 55 functions of the corresponding shafts and supplementary shafts of the aforesaid copending application. It can now be seen that the lost motion effect between the pinion 37 and the wheel 107 is provided so that 60 the pawls 75 and 77 may be operated during

the first step of movement of the pinion 37 to permit operation of the dial and lock part of the carry mechanism. In this way the lost motion effect in the actuating mechanism allows the elimination of the supplementary shafts of the copending application thus eliminating heavy parts, greatly simplifying the construction, and cheapening its production.

The so-called lost-motion device hereinbefore described not only provides a period during the initial movement of each key for the actuation of the carry control mechanism, but it possesses other practical advantages which contribute to greater efficiency 75 in the operation of the machine. By providing lost motion in the dial actuating pinion, the pressure necessary to initiate the depression of a key is greatly reduced for the reason that the number of parts to be set in motion from a standstill and, hence, the inertia to be overcome upon the commencement of the down stroke of the key, is reduced. Also, the spring connecting the pinion and the coöperating ratchet wheel acts 80 to turn the pinion and it thereby maintains a thrust between the teeth of the pinion and its actuating sector, thus taking up backlash between the pinion and sector and, hence, insuring proper reengagement of the 85 dial-actuating ratchet mechanism when the ratchet wheel and pinion return to normal position. This yieldable lost motion device furthermore arrests the return movement of the pinion and coöperating ratchet 90 95 wheel to normal position without shock or jar and it prevents rebound of the ratchet wheel when the latter returns to normal position against its stop, due to the action of the spring which yieldingly presses the stop 100 on the ratchet wheel against the fixed stop.

Without limiting myself to the specific mechanism herein shown, what I claim is:—

1. In a calculating machine, dials, keys, actuating mechanism for the dials comprising an actuator adapted to rotate the dial in response to depression of a key, a driving wheel for advancing the dial in response to the depression of a key, an intermediate yieldable means between the dial driving wheel and the actuator to permit a slight depression of the key in advance of the movement of the dial driving wheel.

2. In a calculating machine, dials, keys, actuating mechanism for the dials operated by the keys and comprising a gear sector, a pinion geared to the sector, a dial driving wheel, and intermediate means between the pinion and the dial driving wheel yieldable to permit a greater angular movement to the 110 pinion than to the dial driving wheel and operative to take up backlash between the 115 pinion and sector.

3. In a calculating machine, keys, dials, and dial-actuating mechanism operative in 120 125 130

response to the depression of the keys and comprising a ratchet mechanism for rotating the dials in response to the depression of a key, and connections intermediate said ratchet mechanism and the keys to permit a slight depression of a key in advance of the operation of the ratchet mechanism.

4. In a calculating machine, dials, keys, dial-operating mechanism operative in response to the depression of a key and comprising a ratchet mechanism for rotating the dials in response to the depression of a key, connections including a pinion with a slot, a stop for positioning said ratchet mechanism in normal position, a pin adapted to engage in the slot and connected to the ratchet mechanism, and a spring normally tensioning pin to a rearward position, thus holding the ratchet mechanism against said stop, the slot, pin and spring co-acting to permit a slight depression of a key in advance of the operation of said ratchet mechanism.

5. In a calculating machine, keys, dials, actuating mechanism for each dial including two driving elements one of which is advanced to actuate the dial simultaneously with and in response to the depression of a key and the other of which elements is advanced in the direction of advance of the first mentioned element only after the first mentioned element has advanced to a predetermined extent, a stop for positioning the second mentioned element in normal position, and a spring acting on said second mentioned element to hold it in normal position against said stop.

6. In a calculating machine, keys, dials, actuating mechanism for each dial, including a ratchet connection comprising an element having a positive reciprocatory movement to advance the dials in response to a stroke of a key and a dial actuating element adapted to be driven to advance the dial by the first named element, the first named element having a greater movement than the dial actuating element and making one step of its movement before the movement of the dial actuating element commences, and spring means for tensioning both of said elements toward a retracted position when at rest.

7. In a calculating machine, keys, dials, actuating means for the dials comprising driving wheels adapted to actuate the dials in response to the depression of the respective keys and engaging wheels adapted to be actuated by the respective driving wheels, and means for rendering the engaging wheels inoperative until the keys have been slightly depressed.

8. In a calculating machine, dials, columns of keys, actuating mechanism for each dial comprising a movable member common to a column of keys, a pinion operative by said member, a dial driving wheel adapted to be

operated by said pinion, a lost motion connection between said pinion and wheel, whereby the pinion is moved first in advance of said wheel and is subsequently moved in the same direction and in unison with said wheel, causing the latter to advance the dial, and spring means for tensioning both the pinion and said wheel toward a normal position.

9. In a calculating machine, dials, a driving sector, means comprising two members, one of which is in mesh with the driving sector and the other of which is rotatively connected with the dial, and a yieldable connection between the two members whereby said members are given different angular movements in the same direction by each actuating stroke of the sector to effect rotation of the dial.

10. In a calculating machine, dials, actuating mechanisms for the dials, each comprising a driving member, a driven member, and co-acting connections between said members whereby the driving members are permitted to advance one step from normal position before becoming interengaged for movement as one with the driven member, and a series of fixed stops arranged to hold the driven members in a normal position one step in advance of the driving members.

11. In a calculating machine, dials, rotary shafts carrying the dials, ratchet mechanisms for advancing the dials, actuating mechanisms for the dials, each comprising a driving wheel and a driven wheel for actuating the dial, advancing ratchet mechanism, connections between said driving and driven wheels which permit limited relative movements between said wheels whereby the driving wheels are permitted to advance one step before becoming interengaged for continued movement in the same direction and in unison with the driven wheels, stops for determining the normal positions of the driven wheels and means for yieldingly holding said driven wheels normally against said stops.

12. In a calculating machine, dials, actuating mechanisms for the dials, each comprising a driving wheel, a driven wheel having a stop thereon, and means whereby the driving wheel is permitted to advance one step before becoming interengaged for movement in unison with the driven wheel, and a series of fixed stops arranged to be engaged by said stops on the driven wheels when the latter are in normal position to hold said driven wheels one step in advance of the driving wheels.

13. In a calculating machine, an adding dial, a driving sector, connections intermediate the sector and the respective dial to be actuated thereby comprising a driving member actuated by the respective sector, a driven member for actuating the corre- 125

sponding dial, a yieldable lost-motion connection between the two members which permits the driving member to advance a step preliminary to the advance of the driven member and maintains a tension on the driven member to hold the latter from advancing during the preliminary advancing movement of the driving member, and a relatively fixed stop against which said 10 driven member is held by said tension during the preliminary advancing movement of the driving member.

14. In a calculating machine, dials, keys, actuating mechanism for each of the dials 15 adapted to rotate its respective dial in response to the operation of its corresponding key and comprising a pinion operative in direct response to the operation of the corresponding key, a dial-rotating wheel, a lost motion connection between said pinion and 20 wheel for permitting the pinion to act in advance of the dial-rotating wheel, carry control means for each dial, and mechanism operative directly by the dial-actuating 25 mechanism during such advance action of the pinion to actuate said carry control means.

15. In a calculating machine, keys, dials, carry mechanism for the dials, means for 30 controlling the carry mechanism, and dial actuating mechanism operative to advance the dial in response to movement in one direction of a key and including a driving connection permitting part of the actuating 35 mechanism to advance one step during such movement of the key before the operation of the dials is begun, said controlling means being operated during said advance step of movement of said part of the actuating 40 mechanism.

16. In a calculating machine, keys, dials, carry mechanism for the dials, means for controlling the carry mechanism, dial actuating mechanism operative to advance the 45 dial in response to movement in one direction of a key and including a driving connection permitting part of the actuating mechanism to advance one step during such movement of the key before the operation 50 of the dials is begun, said controlling means being operated by said part of the actuating mechanism during said advance step of movement of the latter.

17. In a calculating machine, dials, carry 55 mechanism for the dials, means for controlling the carry mechanism, and dial-actuating mechanism operative to advance the dial in response to movement in one direction of a key and including a pin and slot, one 60 adapted for intermittent action upon the other to permit part of the actuating mechanism to advance one step during such movement of the key before the operation of the dial is begun, said controlling means being

operated during said advance step of movement of said part of the actuating mechanism.

18. In a calculating machine, dials, carry mechanism for the dials, means for controlling the carry mechanism, and dial actuating mechanism operative to advance the dial in response to movement in one direction of a key, said actuating mechanism including a pin and slot, one adapted for intermittent action upon the other to permit part of the 70 actuating mechanism to advance one step during said movement of the key before the operation of the dial is begun, said controlling means being operative by said part of the actuating mechanism during the advance 75 step of the latter.

19. In a calculating machine, dials, keys, rocker shafts operative by the keys, mechanisms for rotating the dials approximately 80 simultaneously with the operation of the respective rocker shafts and each comprising ratchet mechanism for engaging the dials and connections intermediate said ratchet mechanism and the respective rocker shaft, carry mechanism for the dials, and controlling means for the carry mechanism operative 85 by said rocker shaft in advance of the operation of the ratchet mechanism.

20. In a calculating machine, dials, keys, differential actuating mechanism operative 90 by the keys, a rocker shaft operative by said differential actuating mechanism to advance the respective dial in response to the down stroke of a key and having co-acting interlocking ratchet connections whereby the dial 100 is not rotated by the initial part of the down stroke of such key, carry mechanism for the dials, and controlling means for the carry mechanism operative by said rocker shaft during the said initial part of the down 105 stroke of the key.

21. In a calculating machine, dials, carry mechanism therefor, control means for the carry mechanism, actuating mechanisms for each dial comprising a positive element and a dial advancing element having a lost motion connection with said positive element, keys, a member movable differentially by said keys to operate said positive element of the actuating mechanism, and means for operating said control means during the first 110 part of movement of said member and during which step the dials are not operated through the action of said lost motion connection between the positive element and the 115 dial advancing element.

22. In a calculating machine, dials, keys, actuating mechanism for the dials, a shaft for driving the actuating mechanism in response to the down stroke of the keys, carry mechanism for the dials, and control means for the carry mechanism operative by said 120 shaft.

23. In a calculating machine, dials, keys, actuating mechanism for the dials, a shaft for driving the actuating mechanism in response to the down stroke of the keys, carry mechanism for the dials, and control means for the carry mechanism operative by said shaft in advance of the operation of the dials by the actuating mechanism.
24. In a calculating machine, dials, actuating mechanism for each dial, an operating shaft for each actuating mechanism, a bank of keys for each shaft for operating the same, carry mechanism for the dials, and control means for the carry mechanism common to and operated by said shafts. 15
25. In a calculating machine, dials, actuating mechanism for each dial, an operating shaft for each actuating mechanism, a bank of keys for each shaft for operating the same, carry mechanism for the dials, and control means for the carry mechanism common to and operated by said shafts in advance of the operation of the dials by the actuating mechanism. 20

In testimony whereof I affix my signature. 25
JAMES F. MAYS.
